J. VAUDREUIL.
CLOTHES HANGER SUPPORT.
APPLICATION FILED DEC. 26, 1916.

Patented Feb. 19, 1918.

UNITED STATES PATENT OFFICE.

JOHN VAUDREUIL, OF MILWAUKEE, WISCONSIN.

CLOTHES-HANGER SUPPORT.

Specification of Letters Patent. Patented Feb. 19, 1918.

1,256,849.

Application filed December 26, 1916. Serial No. 138,839.

To all whom it may concern:

Be it known that I, JOHN VAUDREUIL, a citizen of the United States, and resident of Milwaukee, in the county of Milwaukee and 5 State of Wisconsin, have invented certain new and useful Improvements in Clothes-Hanger Supports; and I do hereby declare that the following is a full, clear, and exact description thereof.

10 The present invention relates to new and useful improvements in supports, more particularly of that type comprising a bar adapted for abutment of its ends against opposite walls of a closet, or against other 15 supports and being extensible in nature whereby to procure a clamping action of said ends to retain the bar in place.

It is the object of the present invention to provide a clothes hanger support, adapted 20 more particularly for position transversely in a closet, and which is of such structure as to permit a minimum cost of manufacture consistent with sufficient strength and convenience of operation.

25 It is more particularly an object to provide a clothes hanger support comprising a wooden body bar, and to eliminate the necessity of providing and clamping plates at the ends of the support I purpose to provide a 30 body bar of such relatively large diameter that the end thereof presents a sufficient area to form an efficient clamping face without danger of marring the face of the wall.

A still further object resides in the provision of a screw extension means for the 35 support which may be associated with the body bar in a manner necessitating a minimum expenditure of labor and of metal.

With the above and other objects and advantages in view, the invention resides more particularly in the novel combination, arrangement and formation of parts more particularly hereinafter described and pointed out in the appended claim.

45 In the drawing:

The drawing shows a side view, partly in section of a clothes hanger support embodying the present invention.

Referring now more particularly to the 50 drawing, 5 designates the cylindrical wooden body bar of my support, which is of a diameter slightly less than the usual diameter of a clothes hanger hook whereby the outer end face of the bar affords an efficient face for 55 coaction with one of the walls 6 of a closet.

For clampingly engaging the opposite wall 7 of the closet, a cylindrical section 8 is provided of a diameter equal to the diameter of the bar and secured in a recess 9 in the inner end of said block by means of a retaining plate 10 is a headed end 11 of a threaded bolt 12. This bolt extends into a bore 13 in the adjacent end of the body bar 5. To threadedly engage the bolt 12, an interiorly threaded sleeve 14 is provided and this sleeve is 60 driven into the bore 13, and has longitudinal teeth 15 on its outer periphery whereby to provide for its non-rotative securement therein. The outer end of the bushing sleeve is provided with an out-turned annular flange seating against the end of the body bar whereby to limit inward movement of the sleeve, it being noted that the sleeve is 65 equal in length to only a fraction of the length of the recess 13, whereby a considerable economy of metal is procured, it being appreciated that the bolt 12 and consequently the socket 13 would be of considerable length to compensate for desired clamping 70 adjustment of the support.

Thus to secure the support in place it is positioned transversely of the walls 6 and 7 of the closets or any other desired supports and the bolt 12 is rotated to clampingly engage the outer ends of the body bar and 85 block 8 against the walls or other supports, rotative movement of the bolt being facilitated by a transverse opening 17 in its outer end through which may be passed a large nail or other member affording a sufficient 90 leverage.

To provide for a proper spacing of clothes hangers on the support, whereby said hangers may not become massed in a manner preventing ready removal of desired hangers 95 the body bar is provided at suitably spaced intervals with annular hook seating grooves 18.

By forming the body bar 5 and screw swivel block 8 of relatively large diameter I 100 not only provide a maximum strength sufficient to meet any unusual strain of use, but I provide end faces for the block and body bar which are of sufficient area to form clamping faces engageable with the walls in 105 a manner preventing injury thereto. Thus the necessity of providing clamping heads on the ends of the support is obviated, and I find that the extra cost incidental to my relatively large diameter of the body block is 110

more than off-set by the eliminated cost of material and labor incidental to providing end clamping heads.

I am aware that extensible supporting rods of the present general nature have been heretofore contemplated, and I therefore do not claim broadly the idea of a support extensible in nature to clamp its ends against opposed walls.

10 My invention is directed more particularly to the described peculiarities of structure which assume a vital importance in the cost of manufacture of the device in necessarily large quantities.

15 What is claimed:

A clothes hanger support comprising a wooden body bar, provided in one end with a longitudinal bore having its mouth counter-bored, an internally threaded sleeve positioned in the counter bore, gripping teeth

20 on the periphery of the sleeve for retaining

the same in fixed relation with the body bar, an annular flange at the outer end of the sleeve and abutting the end of the body bar, said sleeve being of lesser length than the bore, a bolt threadedly engaged in the sleeve and extensible into the bore, a cylindrical section forming a clamping bore and being provided with a recess for receiving a head formed upon said bolt, said cylindrical section being of a diameter equal to that of the body bar, and means for retaining said bolt head in the recess of the cylindrical section substantially as described.

In testimony that I claim the foregoing I have hereunto set my hand at Milwaukee, in the county of Milwaukee and State of Wisconsin, in the presence of two witnesses.

JOHN VAUDREUIL.
